ROTATIONAL KNOB FOR CONTROLS AND THE LIKE

Ralph F. Rogers, Goshen, Ind., assignor to Penn Controls,
Inc., Wheaton, Ill., a corporation of Delaware

Filed June 16, 1967, Ser. No. 7,502

Term of patent 14 years

(Cl. D26—13)

FIGURE 1 is a front elevational view of a rotational knob for controls and the like embodying my new design.

FIGURE 2 is a side elevation with a portion broken away to show the configuration of the face of the knob.

FIGURE 3 is a cross sectional view of the subject rotational control knob taken along the lines 3—3 of FIGURE 1.

I claim:

The ornamental design for a rotational knob for controls and the like, as shown.
